DESIGN FOR A RECIPE BOX

Martha H. Connor, Baltimore, Md., assignor to Owens-Illinois Can Company, Wilmington,
Del., a corporation of Delaware

Application February 1, 1937, Serial No. 67,371

Term of patent 7 years

To all whom it may concern:

Be it known that I, Martha H. Connor, a citizen of the United States, residing at Baltimore, in the State of Maryland, have invented a new, original, and ornamental Design for a Recipe Box, of which the following is a specification, reference being had to the accompanying drawing, forming a part thereof.

The drawing is a perspective view of a recipe box showing my new design, the characteristic feature of which resides in the application of the surface decoration upon the front of the recipe box in the manner shown.

I claim:

The ornamental design for a recipe box, substantially as shown and described.

MARTHA H. CONNOR.
